UNITED STATES PATENT OFFICE.

WALTER MORTON, OF WINDSOR, ONTARIO, CANADA.

CARBURETER.

1,274,070.

Specification of Letters Patent. Patented July 30, 1918.

Application filed August 20, 1915. Serial No. 46,408.

To all whom it may concern:

Be it known that I, WALTER MORTON, a subject of the King of England, residing at Windsor, in the county of Essex and Province of Ontario, Canada, have invented certain new and useful Improvements in Carbureters, of which the following is a specification, reference being had therein to the accompanying drawings.

10 This invention relates to carbureters of the type in which the proportionate admixture of air and fuel is automatically controlled by a member operated by engine inspiration, and its object is to prevent the 15 vibratory movement of this member with each engine impulse and thus insure its even opening or closing as the speed of the engine increases or decreases, to admit the proper amount of air and prevent noise. A further 20 object is to simplify and cheapen the construction of carbureters of this type and to provide an arrangement of fuel inlet whereby the fuel is evenly and positively supplied to the ingoing air, and said inlet may be 25 easily and accurately adjusted or freed from any obstruction.

With these and other ends in view, the invention consists in the construction herein-after more fully described and broadly set 30 forth in the appended claims, reference being had to the accompanying drawings in which—

Figure 1 is a side elevation of a carbureter, embodying the invention with parts 35 broken away to more clearly show the construction;

Fig. 2 is a longitudinal vertical section of the same; and

Fig. 3 is a sectional detail illustrating a 40 locking device.

In the drawings, a preferred construction and arrangement of parts has been shown, but it will be understood that the parts may be given other forms or relative positions 45 within the scope of the appended claims.

The carbureter illustrated in the accompanying drawings comprises a suitable body 10 forming a mixing chamber 11 therein which is contracted slightly toward its lower 50 end and opens through the upper end of the body which is provided with apertured ears 12 by means of which it may be attached to an intake manifold (not shown) of an internal combustion engine. A circular flange 55 13 on the body forms a cover for a bowl or

fuel chamber 14 which is internally screw-threaded at its rim to engage a depending flange 15 on the cover, which flange is partially severed from the cover by a horizontal saw cut 16 and this portion cut in two vertically to form a spring portion 17 of the flange adapted to be expanded within the rim of the cup to frictionally hold the cup against turning upon the body. The spring portion or finger 17 is sprung outwardly or expanded by means of a wedge block 18 engaged between the free end of the finger and the adjacent solid end of the flange and is carried by a screw-threaded stem or bolt 19 extending upward through an opening 70 in the cover and provided with a suitable nut 20 on its upper end.

Formed integral with the bottom of the cup or bowl 14 is an axial tubular portion 21 which extends upward therein, and on 75 the body 10 is a depending tubular member 22 to extend downward within the fuel chamber of the cup and fit loosely over the tubular portion 21. The upper end of the tube 21 is contracted at 23 so that its internal diameter will correspond with the internal diameter of the contracted lower end of the mixing chamber 11 and an annular internal shoulder 24 on the lower end of the body is provided to oppose the upper end of 80 the tube 21, the external diameter of the contracted upper end 23 of the tube being slightly less than the internal diameter of the correspondingly formed portion of the bore of the depending tubular member 22, so that 85 a very narrow annular space or passage 25 is formed between the walls of the two tubes to provide a passage for fuel from the cup to rise therein and be drawn out through the annular space 26 between the upper end 90 of the member 21 and the shoulder 24 when the cup is adjusted upon the body in such a manner as to leave such space, which space 26 thus forms an annular spray orifice for the gasoline. This adjustment is effected by 100 turning the cup up or down upon the flange 15 and locking it in adjusted position by means of the wedge block 18 as above described.

A float 27 within the fuel chamber is 105 hinged at 28 to the body and controls the admission of gasoline to the chamber by means of a valve pin 29 in a passage 30 formed in the body and communicating through a valve seat 31 for the pin with a 110

horizontal passage 32 in the body, into which latter passage the end of a suitable supply pipe 33 leads.

The tubular member 21 of the cup forms 5 with the mixing chamber an axial air passage through the carburetor, and said tube 21 is extended below the bottom of the cup and provided with air inlet openings 34. The lower end of the tube 21 is closed by 10 a disk 35 engaging the end of the tube and formed with an axial upwardly extending guide sleeve 36 to receive the tubular stem 37 of an air control member 38 or head fixed on the upper end of the stem and of a double 15 conical form with its largest diameter normally adjacent the contracted end of the tube 21 and annular fuel inlet 26. The contracted upper end of said tube 21 and contracted lower end of the mixing chamber 20 form a contraction of the air passage through the carburetor with the fuel inlet opening into said passage at its most contracted point, and the passage is further restricted by the head 38 located within this 25 contracted portion so that when the air controlling member or head is in normal position, a narrow space only remains between it and the narrow portion of the air passage through which the air may pass. This re- 30 striction of the air passage at the point where the fuel enters, gives a strong suction on the annular inlet 26 to draw the gasolene in and the ingoing air is always deflected toward said inlet by the lower inverted coni- 35 cal surface of the head.

The stem 37 of the air control member is arranged to slide freely in its guide sleeve 36 and when said member is moved downward as will be hereinafter described, the 40 space around the head 38 is increased, due to the contraction of the upper end of the tube 21 and the tapering upper end of said head.

A cup or cylinder member 39 has a screw- 45 threaded flange to engage the lower end of the tube 21 and is provided with an internal shoulder 40 forming a seat for the disk 35 so that the edge of said disk is engaged between the end of the tube and said shoulder and the 50 disk securely seated and held upon the end of the tube to close the same. Secured upon the lower end of the tubular stem 37 of the air control member is a piston 41 within the cylinder 39 and a series of holes 42 in the 55 wall of the cylinder admits air thereto above the piston. A spring 43 in the cylinder normally holds the piston up against the disks 35 and the air control head 38 in normal position within the contracted portion of the 60 air passage. The interior of the cylinder below the piston is in communication with the mixing chamber 11 through the tubular stem 37 and thus upon inspiration of the engine to which the carburetor is attached, a partial 65 vacuum will be formed in the cylinder be-

low the piston and the air control member will be drawn down against the action of the spring 43, increasing the area of the restriction in the air passage around the head 38 and varying the proportion of air to that 70 of fuel as the speed of the engine increases. The air control member is thus moved in a direction opposite to that of the ingoing air by the inspiration of the engine which creates a partial vacuum in the cylinder 39, 75 and thus the control member is moved gradually as the speed of the engine increases without being directly moved by each engine impulse. Fluttering or vibration of said air control member is thus prevented 80 and the consequent noise and wear common to this type of carburetor is eliminated.

Surrounding the downwardly projecting end of the tube 21 is an air inlet member 44 loosely held between the bottom of the 85 cup 14 and a flange 45 on the cylinder 39 so that the cup may be turned freely to adjust the fuel inlet 26 without turning said member which is formed with a tubular extension 46 at one side for the inlet of air there- 90 to or the attachment of an air inlet pipe (not shown). A choker valve 47 of the usual form is provided in the extension 46 to shut off the supply of air and increase the vacuum in the mixing chamber to cause a 95 greater suction on the fuel inlet in starting, and a throttle valve 48 of the usual form is provided in the outlet end of the mixing chamber.

By this construction a strong mixture is 100 secured for starting the engine and at low speeds due to the arrangement of the annular fuel inlet relative to the air control member, and a quietly operating device giving an even gradual increase in the supply 105 of air as the speed increases, is secured. The arrangement of parts also gives a ready and accurate adjustment of the fuel inlet by the turning of the cup 14 relative to the body, 110 said cup being preferably provided with markings or graduations 49 to aid in such adjustment. Should the fuel inlet 26 become clogged, it may be readily cleaned by turning the cup and the carburetor is readily assembled or taken apart by unscrewing 115 the member 39 which serves to hold the parts in place. The annular inlet 26 admits the gasolene in a thin film all around the air passage, thus insuring an even mixture as it has a greater diameter than the stream of 120 ingoing air and is projected inwardly across said stream, and the air is deflected by the lower side of the head 38 toward the inlet, and other advantages are due to the construction and arrangement of parts.

Having thus fully described my invention what I claim is.

1. In a carburetor, the combination of an air passage having an annular fuel inlet, a fuel chamber concentric with said air pas- 130

- sage and communicating with said annular inlet, and a member within said air passage opposite said fuel inlet and adapted to be moved by engine inspiration in a direction 5 opposite to the flow of the ingoing air in said air passage.
2. In a carbureter, the combination of a body formed with an air passage extending therethrough having a Venturi restriction 10 intermediate its ends and an annular fuel inlet in the wall of said passage completely encircling said passage at the restricted portion thereof, a fuel chamber on the body communicating with said annular fuel inlet, 15 an air regulating member in said passage opposite said fuel inlet, and means for causing said regulating member to be moved longitudinally of the passage by engine inspiration in a direction opposite to the flow 20 of the ingoing air.
3. In a carbureter, the combination of a body having an air passage extending therethrough, the wall of said passage being formed by relatively adjustable members one 25 of which has an annular shoulder opposed by the end of the other member to form a continuous annular opening in the side of said passage for the admission of fuel thereto, means for relatively adjusting said members 30 to vary said opening, a fuel chamber surrounding said passage for supplying fuel to said annular opening, and an air regulating member in the axis of the air passage movable longitudinally thereof and having a 35 head adjacent the fuel opening and spaced from the wall of said passage with an air passage through the head and a closed chamber communicating with the passage.
4. In a carbureter, the combination of a 40 body having an air passage therethrough which is contracted intermediate its ends, the wall of said passage being provided with a fuel inlet at the contracted portion thereof, an air regulating member extending up- 45 wardly in said passage from the inlet end thereof and having a head of double conical form adjacent the contracted portion of the passage with the tapered upper end of said head extending in the direction of the flow, 50 means for causing a movement of said member longitudinally from said contraction in a direction opposite to the flow of the ingoing air upon engine inspiration, and means for supplying fuel to the fuel inlet.
5. In a carbureter, the combination of a 55 body having an air passage therethrough which is contracted intermediate its ends, an air regulating member in the contracted portion of said passage spaced therefrom 60 and having an air passage therethrough, means for supplying fuel to the contracted portion of said passage, a vacuum chamber at one side of said member communicating with the outlet side of said air passage 65 through said air passage in said member, and means adapted by partial vacuum in said chamber for moving the regulating member out of the contracted portion of said passage away from said fuel supply.
6. In a carbureter, the combination of a 70 body having an air passage extending therethrough which is contracted intermediate its ends, means for admitting fuel to the passage at the contracted portion thereof, an air regulating member in said contracted portion of said passage movable longitudinally thereof to vary the space between it and the wall of said passage adjacent the fuel inlet, a cylinder, a piston in said cylinder, a tubular stem connecting the piston and member 75 and through which stem the cylinder communicates with the passage at the outlet side of the contracted portion thereof, and means for moving said member in a direction opposite to that in which it is moved by the piston.
7. In a carbureter, the combination of a body forming a mixing chamber, a cup member forming a fuel chamber concentric with said mixing chamber, and an axial tubular 80 member in the cup co-operating with the mixing chamber to form an air passage through the carbureter and with its end adjacent the body at the lower end of the mixing chamber to form an annular fuel inlet from the fuel 85 chamber into the air passage, said body and cup member being relatively adjustable to vary the fuel inlet.
8. In a carbureter, the combination of a 90 body forming a mixing chamber, a cup member having screw-threaded engagement with the body, an axial tubular member in the cup forming together with said chamber an air passage through the carbureter, the space 95 between the end of said tubular member and body forming a fuel inlet into said air passage which inlet is adjustable by turning the cup relative to the body, and a member within said air passage adjacent said fuel inlet for regulating the flow of air.
9. In a carbureter, the combination of a 100 body forming a mixing chamber, a cup member forming a fuel chamber and having an axial tubular member forming together with the mixing chamber an air passage through 105 the carbureter, the wall of said air passage having an annular fuel inlet adapted to be adjusted to regulate the flow by adjusting the cup member relative to the body, and means for locking the cup in the position to which 110 it is adjusted.
10. In a carbureter, the combination of a 115 body forming a mixing chamber, a cup member detachably secured to the body and provided with an axial tubular member forming together with the mixing chamber a passage through the carbureter, the upper end of said tubular member being in opposed relation to the body to form an annular fuel inlet for said passage, a depending 120
- 125
- 130

- 1 tubular member on the body sleeved over
2 said axial tubular member with a narrow
3 space between said members forming a fuel
4 passage leading to the fuel inlet, said body
5 and cup being adapted to be adjusted relatively
6 to vary the fuel inlet, and means for
7 securing the body and cup in the relative position
8 to which they are adjusted.
- 9 11. In a carbureter, the combination of a
10 body forming a mixing chamber, a cup member
11 on the body provided with an axial
12 tubular member forming together with the
13 mixing chamber a passage through the carbureter, the upper end of said tubular member
14 being in opposed relation to the body
15 to form an annular fuel inlet for said passage and said body and cup being adjustable relatively to vary said inlet, a screw-threaded flange on the body to engage the
16 cup, said flange being severed from the
17 body through a portion of its length to form a yielding expandible portion, and a wedge
18 operable to expand said yielding portion of
19 said flange within the cup and hold the cup
20 and body against turning relatively.
- 21 12. A carbureter comprising a fuel reservoir having an integrally-formed hollow upwardly-extending nozzle through which air to be carbureted may pass, and a cover having an opening and an integrally-formed depending sleeve surrounding said opening and adapted to telescope over said nozzle to form an annular space through which the fuel from the reservoir may pass, the said
- 22 sleeve having an interiorly-formed shoulder 33
23 constituting a valve seat with which the extremity of the nozzle coöperates to control the supply of fuel from said annular space to the space above the nozzle, and said cover having a threaded connection with the reservoir serving as adjusting means for regulating the distance between the extremity of the nozzle and said seat.
- 24 13. A carbureter comprising a fuel reservoir having an integrally-formed hollow upwardly extending nozzle through which air to be carbureted may pass, and a cover having an opening and an integrally-formed depending sleeve surrounding said opening and adapted to telescope over said nozzle to 40
25 form an annular space through which the fuel from the reservoir may pass, the said sleeve having an interiorly-formed shoulder 45
26 constituting a valve seat with which the extremity of the nozzle coöperates to control the supply of fuel from said annular space to the space above the nozzle, and means whereby said reservoir may be raised and lowered with respect to the cover to regulate the distance between the extremity of 50
27 the nozzle and said seat.
- 28 In testimony whereof I affix my signature
29 in presence of two witnesses.
